UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

LOCKER DOOR.

Application filed August 12, 1922. Serial No. 581,389.

My invention relates to lockers of the steel or sheet metal variety, and more particularly to an improved door and locking mechanism therefor.

5 A principal object of the invention is the provision in a structure of this character of an improved mounting for a locking bar adapted to slide lengthwise on the door to move into and from locking position.

10 A further object of the invention is the provision of means for automatically moving the locking bar into locking position upon the closing of the door and for automatically moving it from such position by 15 a mere pull on the handle which protrudes from the front of the door.

Other objects and advantages of the invention will be apparent as it is better understood from the following description, 20 which, taken in connection with the accompanying drawings, discloses a preferred embodiment thereof.

Referring to the drawings:

Figure 1 is a perspective view of the 25 locker in which my invention is embodied;

Fig. 2 is a sectional view looking toward the front from the interior of the locker;

Fig. 3 is an enlarged sectional view of the locking portion of the door with the 30 locking bar in its down, or locked position;

Fig. 4 is a similar view of the locking bar elevated to disengage the same from the locking member on the frame;

Fig. 5 is a detail view of the locking 35 elements which are mounted respectively on the frame and the door;

Fig. 6 is a detail perspective of the flanged portion of the door, showing the manner in which the headed projection is formed;

40 Fig. 7 is a similar view, showing the locking bar in assembled relationship; and

Fig. 8 is a detail sectional view taken substantially on the line 8—8 in Fig. 3.

Upon the drawings, I have shown, for 45 the purpose of illustration, a locker body 11, which, as shown may include a series of lockers with partitions therebetween, each of said lockers being provided with a door 12, which is hinged at 13 upon the front 50 side of a frame 20, the latter being supported upon legs or corner angles 14, or in any desired manner. Attached to the inner side of the frame, opposite the side upon which the door is hinged, are locking lugs 15, which are fixedly secured by rivets

16 and which are formed to provide a hook part 17 into which the flange 18 of the door may extend. The portion of the hook extending toward the door is provided with a notch 19 and the edge therebeyond is beveled, as indicated at 21, to permit automatic locking action, as will be hereinafter described.

Upon the door flange 18 is mounted a 60 sliding locking bar 22, which is provided with offset portions 23, in which are provided locking parts 24, adapted to enter the notches 19 to hold the door in closed position when said bar is locked, against endwise movement. It will be evident that 65 the mere closing of the door will cause the part 24 to ride up the beveled edge 21 of the locking lug and enter the notch 19, so that the bar may be brought to locking position by merely closing the door with slight 70 force.

In the flange 18 of the door, there are 75 provided a desired number of headed projections 25, which are formed by merely cutting out and pressing inwardly a portion 80 of said flange. The projection thereby provided consists of the headed portion 25 and shank parts 26 forming a bearing and guide for the bar. At spaced intervals in the bar are slots 27, which are formed with an enlarged portion 28, the latter being of sufficient area to permit insertion of the head 25 and the remainder of the slots being of merely sufficient size to permit the bar to 85 slide upon the shanks 26 with the heads 25 90 engaging the opposite side of said bar. This construction, it will be seen, permits ready assembly of the locking bar upon the door and removal therefrom when brought to proper position, and, at the same time, firmly secures it in place so that it cannot be 95 removed during normal action and without the removal of a handle to be now described.

A handle 29 is secured to the bar 22 by 100 screws 31, extending through an apertured extension 32 of the handle which passes through a slot 33 in the door. The bar at the point of its attachment to the extension 32 is provided with a projection 30, which 105 extends into the aperture of said extension and behind said projection is a recess 30' in which lies the point of the screw 31. On the lower end of the handle 29 is a cam and locking part 34, in which is an aperture 35. 110

Upon the door is provided a socket 36, of general configuration corresponding to that of the part 34 on the handle and this socket part is provided with an aperture 37. It 5 will be manifest that when the handle is in its down or seated position, the shank of the padlock may be passed through the aligned apertures 35 and 37 to lock the bar 22 against vertical movement. It will also 10 be manifest that outward pull upon the handle 29 will cause the cam surface 38 to ride upon the inner parts of the socket member 36, thereby automatically lifting the bar 22 from locking position and allowing 15 the door to be opened.

It is thought that the invention and many of its attendant advantages will be understood from the foregoing description, and it will be apparent that various changes may 20 be made in the form, construction and arrangement of the parts without departing from the spirit and scope of the invention or sacrificing all of its material advantages, the form hereinbefore described being 25 merely a preferred embodiment thereof.

I claim:

1. A locker comprising a frame, a notched locking lug attached to said frame and having a beveled edge beyond the notch therein, 30 a door, a slideable locking bar mounted on said door and having a locking portion adapted to ride up said beveled edge on said locking lug and enter the notch therein when the door is closed, a handle secured to said 35 locking bar and adapted to be locked to a fixed portion of the door, and a cam on the lower part of said handle adapted to ride upon said fixed portion of the door when the handle is pulled outwardly, to automatically lift the locking bar and open the door.
2. A locker comprising a frame having a beveled locking catch thereon, a door hinged to said frame, a locking bar slidably mounted on said door and having a 45 locking part adapted to automatically engage said beveled catch when the door is closed, and a handle secured to said locking

bar and extending exteriorly of the door, said handle having a cam action upon the door to lift the bar when an outward pull is 50 exerted thereon.

3. A locker door comprising a body, a locking bar slidably mounted on said door, said door having a headed projection struck inwardly therefrom and said bar being provided with a slot having portions of different dimension whereby the headed projection may enter through a portion thereof and retain the bar when engaged behind the smaller portion of said slot, and a handle 60 having a portion adapted to be locked to the door and having a cam action upon the door to lift the bar from locking position when an outward pull is exerted upon said handle.

4. A locker, comprising, a frame, a 65 notched locking lug attached to said frame and having a beveled edge beyond the notch therein, a door, a slideable locking bar mounted on said door and having a locking portion adapted to ride up said beveled edge 70 on said locking lug and enter the notch therein when the door is closed, said door being formed to provide a headed projection and said locking bar having a slot therein, a portion of said slot being enlarged to 75 permit insertion of said headed projection and the remainder being of less width than the headed portion of said projection.

5. A locker, comprising, a frame, a door hinged thereon, a locking catch attached to said frame and having a beveled edge extending toward the door, a locking member slidably mounted upon said door and having an offset adapted to automatically ride upon said beveled edge and enter said notch when the door is forcibly closed, said locking member being provided with a slot comprising portions of different cross-sectional dimension, and said door being formed to provide with a headed projection adapted 85 to pass through the large portion of said slot and to engage the bar adjacent the small portion thereof.

WALTER N. VANCE.
